UNITED STATES PATENT OFFICE.

REGINALD R. BELKNAP, OF UNITED STATES NAVY.

NET.

Application filed May 10, 1917. Serial No. 167,825.

To all whom it may concern:

Be it known that I, REGINALD R. BELKNAP, an officer of the United States Navy, have invented new and useful Improvements in Nets, and, in order that others skilled in the art may understand and practice my invention, I give the following specification thereof, of which the accompanying drawings form a part.

10 The object of my invention is to provide a net that may be used for a variety of purposes, including more particularly its use as a defense against submarine boats and torpedoes. Another object of my invention 15 is to provide a net of such construction as to give it greater flexibility, uniformity of strength, facility and compactness of stowage and facility in handling and transportation. Other objects will appear from the 20 following specification.

In the accompanying drawing I have illustrated one form of my invention, in which:—

Figure 1 represents a general view of a 25 square-mesh net,

Fig. 2 represents a portion of a net having the mesh diamond-shaped,

Fig. 3 is a detail view on a larger scale 30 of the crossing point of the wires or corner of a mesh,

Fig. 4 is a detail on similar scale of a 35 modification,

Fig. 5 is a view on an enlarged scale of one form of a stop and method of securing it on the wires,

Fig. 6 is a sectional view on line 6—6 of Fig. 5, and

Fig. 7 is a view of another way of securing the stop to the wire.

40 In constructing a net in accordance with my invention, I provide a flexible or yielding connection at the corners of the meshes or at the junctions or crossings of the ropes or wires that make up the net and its attachments. I obtain such flexible or yielding connection by providing a ring or link 1, preferably of forged steel, that surrounds the crossings or junctions of the wires; that is to say, each of the crossing or meshing 45 wires 2 and 3 is threaded or passes through said ring so as to make a loose connection, both wires and the ring being loose and not connected to one another, each wire or ring being free to move and adjust itself to a

limited extent independently. To retain the 55 parts in relative position and at the same time to provide for freedom of relative movement, I provide on each wire 2 and 3 the stops 4, 4 and 4', 4'. The two stops 4, 4 on a vertical wire are so arranged as to be 60 at some distance apart and on opposite sides of the ring 1. Also, the two stops 4', 4' on the horizontal wire are similarly positioned and arranged one on each side of the ring 1. These stops, as will be understood, are of a size larger than the internal diameter of the ring; or, if the ring be elliptical or I-shaped, are larger than the greatest internal diameter of the ring, the object being, as will be apparent, to prevent 70 the wires slipping through the ring in either direction more than the limited amount determined by the distance the stops 4, 4 or 4', 4' are placed apart, respectively, on their wires. For example, the amount of slipping or movement in either direction may be an inch or two, allowing for a play of some three inches,—this being, however, merely an illustrative example.

The stops 4, 4' may be made in any suitable or convenient manner. They may consist of forged steel clamps made either in separate or hinged halves, as in Fig. 7, the two halves that form one stop being riveted or otherwise clamped together and also to 80 the wires or ropes that constitute the net. Or, they may be made of a tough, tenacious alloy of a comparatively low melting point and may be molded directly on the wire, as in Fig. 3. In order to insure the stops 4 85 or 4' on the wires from displacement, I may transfix them to the wires by means of pins 5, 5, thrust between the strands, as seen in Figs. 5 and 6. Two such pins arranged transversely one to the other are 90 shown in the drawing as securing one stop 4; but it will be understood that only one such pin may be used if desired, or any suitable number. If the stop be cast upon the wire, it may be cast about such pins; or, if 95 a previously-formed stop be used, perforations may be provided therein and the pins inserted therethrough and driven between the strands. The object, as will be understood, is to firmly secure the stops to the 100 wires against displacement.

It will be understood that such ring and stop connection will occur at each corner of

the meshes of the net, as illustrated in Figs. 1, 2 and 3,—the ring being in the midst of four stops on the crossing wires and surrounding both wires at the point of crossing or intersection.

This form of loose and flexible connection between the wires forming a net may be employed with advantage at other points than at the mesh corners, as for example, where 10 the mesh wires are connected to either or both the top and bottom edge or selvage wires 3^a, 3^b, or to the end wires 2^a, 2^b. At such points a wire terminating at a selvage or end wire may be provided near its end 15 with two stops similarly secured to the wire and arranged one on either side of a ring 1^a. Such ring 1^a will surround the end wire 2^a between the stops 4, 4 thereon, and will also surround the selvage wire 3^b.

20 At the top wire of a net the stops 4', 4 are arranged and fixed on the wire at intervals that correspond with the size of the mesh (Fig. 1) and similarly for the end wire 2^a. The vertical wires may have their 25 upper ends eye-spliced or eye-clamped, as shown, and connected to the top wire through rings or links 1^b that are intermediate two stops 4', 4'; this ring being interlinked with the eye-splice and surrounding top-wire 3^a 30 between two stops 4', 4'. The rings 1^b may also be further interlinked with other rings 6, the latter being used for the attachment of buoys, moorings, towing lines, &c.

Instead of having the vertical wires eye-spliced at their ends, a "free-end" construction may be employed, as illustrated in Fig. 4. In this form of construction the end of the wire 2 is provided with the spaced-apart 40 stops 4, 4, between which and surrounding wire 2 is the ring or link 1^b, the latter also surrounding wire 3^a, and also interlinked with ring or eye 6. The advantage of such 45 "free-end" construction is that it reduces or eliminates the liability of the net to kink, twist, and spring, that tends to accumulate in the several wires, and in the net as a whole with handling, setting, &c.

From the foregoing description it will be seen that the constituent wires of a net made 50 in accordance with my invention are not interwoven or interlaced one with the other, but are separate and disjoined though held securely in their relative positions to form the fabric by the rings or links that surround the wires at their crossing or junction points.

By means of my invention a net may be formed either of rectangular mesh, as illustrated in Fig. 1, or with a diamond mesh, as 60 illustrated in Fig. 2. In a net of the former kind the wires may be continuous throughout the length and width, respectively, of the net and the net may be as long as desired, the longitudinal wires being continuous throughout. This avoids the necessity

of splicing or joining the wires with the advantage of securing greater uniformity of strength and avoiding weakness and other objections of splices or joints. For example, a net of 36 feet width or depth may be 70 made as long as desired in one section, the longitudinal wires being arranged, say, 12 feet apart and crossed every 12 feet by 36 feet lengths of the same wire, thus making a mesh 12 feet square. The ends of the crossing or vertical wires may be eye-spliced or eye-clamped, and the top and bottom longitudinal wires rove through the eyes. Where the wires cross both wires are rove 75 through the steel links, with a stop secured 80 on each wire each side of the ring and at such distance apart as to allow freedom of movement between the wires at this junction or intersection, as before explained.

In making a net with diamond meshes, 85 vertical wires may be eliminated and all wires may be made of equal length and continuous throughout the net, thus making for uniformity of strength and readiness in assembling and manufacture.

90 One of the important advantages of a net made in accordance with my invention is the facility with which it may be collapsed, stowed and handled. It will be seen that if taken up by one corner, or if pulled at diagonally opposite corners, it will collapse like a handkerchief or an umbrella, and may be coiled and carried on a reel—the most compact form for stowage, handling and laying. The joints or crossings of the wires 95 100 are sufficiently loose and flexible to permit the wires to lie approximately parallel within the rings and at the same time to permit the same to lie at any angle with each other up to 90 degrees without bend or nip. The 105 rings also lie approximately parallel with the wires when the net is collapsed.

This increased flexibility of my improved net not only makes for facility in handling and stowage, but materially increases its 110 draping or fouling effect about a submarine or torpedo.

A net constructed in accordance with my invention is also less expensive to construct and is lighter, size for size, than nets of other construction. Also, my net is simpler, and requires less time to construct or manufacture. There are fewer and smaller projections and consequently there is less fouling or liability to catch or snag as the net 120 is dragged over the side or deck of a boat in planting or laying.

125 While I have referred to the advantages of a net constructed in accordance with my invention for naval purposes, it will be understood that there are many other uses in which my invention is valuable and for which a net is commonly employed,—whether for a barrier or where a net is required to be temporarily erected on land or 130

to be collapsed and transported, or where a net may be required to be quickly manufactured. It will be seen that in order to manufacture one of the nets no factory or shop appliances or machinery is necessary. All that is required is a supply of wire or rope with a stock of rings or links and stops or means for casting or clamping or forming or affixing the latter to the wires. With these and simple hand appliances or tools, nets may be readily constructed and in places remote from shops or factory facilities.

It will be understood that modifications from the exact form and shape of the rings and stops and their engagement with the wires shown in the drawings may be made without departing from the invention.

What I claim is:

1. A net formed of separate or disjoined wires, stops on said wires on either side of their crossing or junction points, and rings surrounding said wires and co-operating with said stops to hold said wires in their relative positions.
2. A net formed of free lengths of wires crossing one another at intervals corresponding to the meshes of the net, stops on each of said wires arranged one on each side of their crossing points, and rings or links surrounding both wires at their crossing points and intermediate the stops on both wires.

3. Means for connecting the constituent wires of a net, said means consisting of a pair of spaced-apart stops on the wire and a ring or link loosely surrounding the wire between said stops, whereby the wire is capable of movement within the ring, said movement being limited longitudinally of the wire by the engagement of the stops with the ring.

4. A net formed of free lengths of wires arranged crosswise of one another in mesh-forming relationship, rings or links separate from said wires and loosely surrounding both wires at the crossing or junction points and permitting said wires to move angularly with respect to one another, pairs of spaced-apart stops fixed to or formed on said wires, one stop of said pair being on each side of a crossing or junction point and each side of the said ring thereat, whereby the constituent wires of said net have freedom of longitudinal movement limited by the engagement of said stops and rings.

In witness whereof, I have hereunto signed my name in the presence of two subscribing witnesses.

REGINALD R. BELKNAP.
